US00D775195S

(12) **United States Design Patent** (10) **Patent No.:** **US D775,195 S**
Caldwell et al. (45) **Date of Patent:** **** Dec. 27, 2016**

(54) **DISPLAY SCREEN OR PORTION THEREOF WITH A GRAPHICAL USER INTERFACE**

(71) Applicant: **MX Technologies, Inc.**, Lehi, UT (US)

(72) Inventors: **John Ryan Caldwell**, Lehi, UT (US); **Ronald Brennan Knotts**, Provo, UT (US); **Jonathan R. Hopkins**, Pleasant Grove, UT (US)

(73) Assignee: **MX TECHNOLOGIES, INC.**, Lehi, UT (US)

(**) Term: **15 Years**

(21) Appl. No.: **29/556,878**

(22) Filed: **Mar. 3, 2016**

Related U.S. Application Data

(63) Continuation of application No. 29/543,025, filed on Oct. 20, 2015, now Pat. No. Des. 752,083, and a continuation of application No. 14/481,772, filed on Sep. 9, 2014.
